CLAIM

An ornamental design for an electronically detectable tag with clamp and clutch locking mechanism, as shown and described.

DESCRIPTION

FIG. 1 is a top perspective view showing the new design; FIG. 2 is a top plan view thereof;

FIG. 3 is a bottom plan view thereof;

FIG. 4 is a right side elevational view thereof;

FIG. 5 is a left side elevational view thereof;

FIG. 6 is a front elevational view thereof; and,

FIG. 7 is a rear elevational view thereof.

The surface indicia illustrated by broken lines in FIGS. 1, 2, 8, and 11 do not form part of the ornamental design, and are merely exemplary of surface indicia that can be applied. In use, the electronically detectable tag with clamp and clutch locking mechanism is attached to articles such as eyeglasses, jewelry, watches, and other articles, to electronically protect and/or identify the article.
